(57) **CLAIM**

The ornamental design for a light fixture component, as shown and described.

DESCRIPTION

This application is related to commonly owned concurrently filed U.S. design patent applications Ser. No. 29/197,687; Ser. No. 29/197,606; Ser. No. 29/197,606; Ser. No. 29/197,600; Ser. No. 29/197,608; and Ser. No. 29/197,619.

FIG. 1 is a front elevational view of the light fixture component of the present design, a rear elevational view being a mirror image thereof;

FIG. 2 is a left side elevational view thereof;

FIG. 3 is a right side elevation view thereof;

FIG. 4 is a top plan view thereof;

FIG. 5 is a bottom plan view thereof; and,

FIG. 6 is a front elevational view of a light fixture incorporating the light fixture component therein.

The broken lines shown are for illustrative purposes only and form no part of the claimed design.
